(57) **CLAIM**

The ornamental design for a display screen or portion thereof
with animated graphical user interface, as shown and
described.

DESCRIPTION

FIG. 1 is a front view of a display screen or portion thereof
with animated graphical user interface showing a first image
in the sequence showing my new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof;

FIG. 12 is a front view of a twelfth image thereof;

FIG. 13 is a front view of a thirteenth image thereof; and,

FIG. 14 is a front view of a fourteenth image thereof.

The dashed lines in the Figures, including the display screen,
show portions of the animated image and display screen
which form no part of the claimed design.

The dot dash broken lines in the Figures show an unclaimed
boundary and do not form part of the claimed design. They
show the relationship between the area within the dot dash
broken line, which is not claimed, and the shape of the rest of
the Figure, and in particular, the movement of the area about
the display screen.

The appearance of the animated image sequentially transitions
between the images shown in FIGS. 1-14. The process
or period in which one image transitions to another forms no
part of the claimed design.
